COTTON ROLL HOLDER

Jack C. Kanter, Norfolk, Va.

Application December 22, 1950, Serial No. 202,190

3 Claims. (Cl. 32—35)

1

The present invention relates to dental appliances, and is particularly concerned with improvements in holders for holding cotton rolls which are used to maintain parts of the teeth in a dry condition.

One of the objects of the invention is the provision of an improved cotton roll holder which holds a roll of cotton in the upper cheek, which is self-adjusting, which cannot become displaced while being used, and which provides a clear operating field for easy access to all the upper and lower teeth without obstructions or interference on the part of the appliance.

Another object of the invention is the provision of an improved cotton roll holder which occupies a minimum space, which permits access to the buccal surface of the upper posterior teeth, and which has no connecting bands crossing over the occlusal surface of the lower teeth, which would limit access and vision.

Another object of the invention is the provision of an improved cotton roll holder which is more efficient and more comfortable than the devices of the prior art, and which maintains a complete dryness by retaining a third upper cotton roll in the buccal fold of the maxilla.

Another object of the invention is the provision of an improved cotton roll holder in which the spring pressure adjusts itself and aids in keeping the patient's mouth open, and which permits sodium fluoride therapy being rendered without necessity for manually holding cotton rolls in position.

Another object of the invention is the provision of an improved cotton roll holder which is simple in construction, durable, capable of economical manufacture, and adapted to be used upon patients of different size and characteristics.

Other objects and advantages of the invention will be apparent from the following description and the accompanying drawings, in which similar characters of reference indicate similar parts throughout the several views.

Referring to the drawings,

Fig. 1 is a view in perspective showing a device embodying the invention, in position to hold cotton rolls on each side of the lower left teeth, and a third cotton roll outside the adjacent upper teeth;

Fig. 2 is an enlarged side elevational view of the lower cotton roll holder;

Fig. 3 is a fragmentary bottom plan view of the holder member of Fig. 2;

Fig. 4 is a transverse sectional view, taken on

2

the plane of the line 4—4 of Fig. 3, looking in the direction of the arrows.

Referring to Fig. 1, 10 indicates in its entirety a cotton roll holder embodying my invention and shown installed with its lower parts on opposite sides of the submaxillary teeth 11. The cotton roll holder preferably is provided with a lower roll holding member 12 and an upper roll holding member 13, which are resiliently secured together for relative movement by means of hinge formations 14 and a biasing spring 15.

The lower roll holding member 12 is preferably of substantially U shape, as seen in Fig. 1, with a pair of forwardly extending arms 16 and 17 joined by a flat yoke 18. The arms 16 and 17 may be regarded as partially tubular members, having a long oval cut-out 19 and 20 in each instance.

The bodies of the arms 16 and 17 are curved at 21 and 22 to substantially cylindrical shape; and these portions are joined by longitudinally extending, diametrically opposite portions 23. The shape and size of the partially cylindrical portions 21 and 22 are such that a cotton roll has a substantial fit in these portions; and the arms 16 and 17 form half cylindrical formations which extend about the cotton rolls slightly more than 180 degrees so that the cotton rolls are retained in the trough 24, which is provided by each of these frames.

The lower edges 25 on each of the side frame members 23 may turn in slightly to retain the cotton rolls; and these edges may be provided with inwardly turned pointed prongs 26, there being two such prongs on each side, and the prongs being located at each end of the arms 16 and 17, projecting inwardly from the lower edges 25.

The cotton rolls 27 and 28 held by the arms 16 and 17, respectively, have their uncovered parts turned downwardly into engagement with the tissues of the mouth between the cheek and the gums; but an upper portion of each cotton roll is exposed in the oval cut-outs 19 and 20 for engaging the sides of the teeth.

The yoke 18 may be substantially flat, and it is curved upwardly at 29 and at 30, rearwardly of the arms 16 and 17, so that the transverse flat portion 31 of yoke 18 is located above the teeth. The rear edge of this flat portion 31 is preferably provided with a pair of partially cylindrical hinge formations 32, separated to receive a similar hinge formation 33 on the upper roll holding member 13; and a headed pin 34 passes

through the hinge formations 32, 33 to mount them pivotally with respect to each other.

The pintle 34 is preferably longer than the hinge assembly 14 and projects laterally sufficient so that coil spring 15 may be wound upon the pintle 34. One end of the coil spring 15 extends tangentially from the coil spring 15 and is laterally turned at 35 to engage the upper side of the flat yoke 18, to which it may be soldered.

At its other end the spring 15 has a tangentially extending arm 36, which is formed with a transverse loop 37 extending about the upper roll holding member 13. The spring 15 has its tangential arms 35 and 36 so bent that they tend to spread the roll holding members, which can be forced together against the tension of the spring.

The upper roll holding member 13 preferably has a curved supporting portion 38 and a partially cylindrical roll holding portion 39. The roll holding portion again may be considered as a half cylindrical member with a long oval cut-out 40. This half cylindrical member has its open side turned upwardly and laterally toward the upper teeth. Here again the edges 41 are located slightly beyond 180 degrees and are turned inwardly to grasp the upper cotton roll 42 and hold it in the upper trough.

At the front and back corners of the side portions 43 of this upper roll holding member 39 there may be inwardly turned pointed prongs 44 for engaging in the cotton roll. The upper trough is twisted, with its oval opening 40 extending downwardly and outwardly so that the cotton roll is presented upwardly and inwardly. This causes the cotton roll to touch the hard tissues of the gum and keeps the metal out of contact with the hard tissues of the gum.

The upper cotton roll is preferably so disposed that it blocks the issuance of secretions from the upper salivary glands.

The end portions 45 and 46 of the roll holding members 16 and 17, and also the upper roll holding member 39, taper toward the transverse portions 21, as seen in Fig. 2.

The device is preferably made of resilient stainless steel and the operation thereof is as follows: Fresh cotton rolls are first placed in all three troughs; and the patient's mouth is thoroughly dried at points where the cotton rolls are to be installed.

The upper roll holding member 13 is then pressed downwardly toward the two lower roll holding members 16 and 17; and the device is inserted in the mouth over the submaxillary teeth.

The operator must provide himself with a left-hand and a right-hand device so that each may be employed on the proper side of the mouth. The lower arms 16 and 17 having been located upon opposite sides of the lower teeth, the upper arm 13 is then permitted to spring upward into the space between the cheek and the upper teeth.

The device is now in such position that the operative field is completely exposed. It is practically impossible to displace the holder by the ordinary movements of the tongue and lips; and no adjustments are necessary on the roll holder. The operative field is completely exposed; and the gentle spring pressure, which urges the upper and lower rolls apart, adjusts itself and aids in keeping the patient's mouth open.

Different sizes should be provided for the mouths of children from those used for adults.

It will thus be observed that I have invented an improved cotton roll holder which holds a roll in the cheek, is self-adjusting, cannot be displaced easily, and provides a completely clear operating field for easy access to all of the upper or lower teeth without any obstruction or interference on the part of the appliance. Maximum accessibility and vision are provided of the teeth on which work is to be done.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A cotton roll holder for dental use, comprising a substantially U-shaped metal member formed with a backward yoke to be located behind the last molar tooth, the said yoke being formed on its outer rear corner with a hinge formation having a pintle, and the said yoke supporting a pair of forwardly extending legs of substantially half cylindrical shape, said legs being substantially parallel and spaced from each other sufficiently to cause the cotton rolls, which they are to carry, to engage the gums on both sides of the teeth, each of said legs having the body of its partially cylindrical portion cut out over the major portion of its area to form an elongated oval rim, and said partially cylindrical portion having a pair of inwardly extending prongs on each of its sides diametrically inward to engage in a cotton roll, the legs being curved upward adjacent said yoke to bring the yoke into the level of the top of the molars, and an upper member carried by a hinge formation on said pintle, and comprising a sheet metal upwardly and forwardly curved supporting arm provided with an upwardly open half cylindrical metal formation for receiving a cotton roll for engaging the upper and outer gum at the molars, the said upper partially cylindrical formation also having an elongated oval cut-out, and being provided with a pair of prongs on each of its sides, engaging in the cotton roll, and means for urging the upper cotton roll into engagement with the upper gum by reacting against the two lower cotton rolls engaging the lower gums.

2. A cotton roll holder for dental use, comprising a substantially U-shaped metal member formed with a backward yoke to be located behind the last molar tooth, the said yoke being formed on its outer rear corner with a hinge formation having a pintle, and the said yoke supporting a pair of forwardly extending legs of substantially half cylindrical shape, said legs being substantially parallel and spaced from each other sufficiently to cause the cotton rolls, which they are to carry, to engage the gums on both sides of the teeth, each of said legs having the body of its partially cylindrical portion cut out over the major portion of its area to form an elongated oval rim, and said partially cylindrical portion having a pair of inwardly extending prongs on each of its sides diametrically inward to engage in a cotton roll, the legs being curved upward adjacent said yoke to bring the yoke into the level of the top of the molars, and an upper member carried by a hinge formation on said pintle, and comprising a sheet metal upwardly and forwardly curved supporting arm provided

with an upwardly open half cylindrical metal formation for receiving a cotton roll for engaging the upper and outer gum at the molars, the said upper partially cylindrical formation also having an elongated oval cut-out, and being provided with a pair of prongs on each of its sides, engaging in the cotton roll, and means for urging the upper cotton roll into engagement with the upper gum by reacting against the two lower cotton rolls engaging the lower gums, the upper partially cylindrical formation having its open side turned inward to provide an unobstructed cotton roll area on the inner upper side of the upper roll.

3. A cotton roll holder for dental use, comprising a substantially U-shaped metal member formed with a backward yoke to be located behind the last molar tooth, the said yoke being formed on its outer rear corner with a hinge formation having a pintle, and the said yoke supporting a pair of forwardly extending legs of substantially half cylindrical shape, said legs being substantially parallel and spaced from each other sufficiently to cause the cotton rolls, which they are to carry, to engage the gums on both sides of the teeth, each of said legs having the body of its partially cylindrical portion cut out over the major portion of its area to form an elongated oval rim, and said partially cylindrical portion having a pair of inwardly extending prongs on each of its sides diametrically inward to engage in a cotton roll, the legs being curved upward ad-

jacent said yoke to bring the yoke into the level of the top of the molars, and an upper member carried by a hinge formation on said pintle, and comprising a sheet metal upwardly and forwardly curved supporting arm provided with an upwardly open half cylindrical metal formation for receiving a cotton roll for engaging the upper and outer gum at the molars, the said upper partially cylindrical formation also having an elongated oval cut-out, and being provided with a pair of prongs on each of its sides, engaging in the cotton roll, and means for urging the upper cotton roll into engagement with the upper gum by reacting against the two lower cotton rolls engaging the lower gums, comprising a coil spring having outwardly extending ends urging apart the two parts hinged on said pintle, the cotton rolls staying in place automatically during any position of opening or closure of the mouth of the patient.
